UNITED STATES PATENT OFFICE.

LAZARD KAHN, OF HAMILTON, OHIO, AND ADAM SPECK, OF DETROIT, MICHIGAN, ASSIGNORS TO F. & L. KAHN & BROS., OF HAMILTON, OHIO.

DESIGN FOR A GAS-RADIATOR.

SPECIFICATION forming part of Design No. 24,556, dated August 13, 1895.

Application filed May 31, 1895. Serial No. 561,334. Term of patent 14 years.

To all whom it may concern:

Be it known that we, LAZARD KAHN, a resident of Hamilton, Butler county, Ohio, and ADAM SPECK, a resident of Detroit, Michigan, 5 citizens of the United States, have invented a certain new and original Design for a Gas-Radiator, (Case A,) of which the following is a specification.

Our design for a gas-radiator is shown in 10 the accompanying drawing, which is a perspective view of the radiator.

The leading features of our design are the burner-chamber, the base, the legs, the burner-chamber door, the tube-escutcheons, and the 15 top when those parts have the peculiar characteristics herein set forth.

The horizontal burner-chamber A has convex ends ornamented by foliate scrolls in low relief.

20 The base B has its front curtain ornamented by a central drop shield bearing foliate scrolls and flanked by foliate scrollwork extending to the ends of the base.

The legs H have their sides ornamented by 25 volute scrolls, the volutes projecting outwardly at the tops of the legs at the line of juncture with the base. The faces J of the legs below the volutes are smooth and curved inwardly and are convex horizontally, and

these faces are vertically divided by the ornamental tongue J in low relief.

The burner-chamber door C is segmental in vertical cross-section and is ornamented by a central foliated jeweled escutcheon intertwining with open foliate scrollwork extending to 35 the end margins of the door.

The radiating tubes D are ornamented at their bases by escutcheons E, and at their tops by escutcheons F, which have margins in the form of converging foliate scrolls, the 40 space between the margins being filled by diagonal cross-bars.

The radiator-top G has its curtain ornamented by foliate scrolls in relief, with the irregular lower outline of the scrollwork forming the lower contour line of the curtain.

We claim—

The design for a gas radiator, substantially as described and shown.

LAZARD KAHN.
ADAM SPECK.
